UNITED STATES PATENT OFFICE

2,353,040

RECOVERY OF STYRENE

Minor C. K. Jones, Westfield, and Alfred A. Wells, Roselle Park, N. J., assignors, by mesne assignments, to Jasco, Incorporated, a corporation of Louisiana

Application February 27, 1941, Serial No. 380,798

5 Claims. (Cl. 260—669)

The present invention is concerned with the recovery of styrene. The invention is more particularly concerned with a novel sequence and arrangement of stages by which styrene may be efficiently and economically recovered and segregated from feed streams containing the same utilizing picric acid. A preferred modification of the process comprises closely fractionating styrene containing feed mixtures to produce a relatively narrow boiling range fraction, which fraction is subsequently treated under definite conditions with an aqueous solution of picric acid. The picric acid solution is subsequently treated in a manner to segregate and recover the styrene.

It is known in the art that hydrocarbon fractions derived from various sources, such as those derived in the processing of petroleum oils, as well as hydrocarbon fractions produced in the manufactured gas industry, contain various quantities of styrene. Since styrene comprises an essential and valuable feed material in many processes, such as in the manufacture of artificial rubber, various processes have been suggested for recovering this material. We have now discovered a process by which styrene may be efficiently and economically recovered from hydrocarbon fractions containing the same. Our process comprises contacting the styrene containing feed fraction with picric acid either in the solid or in the solution form.

Our process may be readily understood by reference to the attached drawing illustrating an embodiment of the same. The drawing illustrates an adaptation of our invention for the segregation of styrene from hydrocarbon fractions containing the same, utilizing an aqueous solution of picric acid in the treatment of a segregated relatively narrow boiling range feed fraction. Referring specifically to the drawing, it is assumed for the purposes of illustration that the feed stream comprises a hydrocarbon fraction boiling in the range below about 550° F., and is produced in the cracking of petroleum oils. The feed stream is introduced into distillation zone 1 by means of feed line 2. Before introducing the feed into the distillation zone, it is heated in heating zone 3 to the desired temperature. Temperature and pressure conditions in zone 1 are adapted to remove overhead by means of line 4 relatively low boiling hydrocarbon constituents and to remove as a bottoms by means of line 5 relatively high boiling hydrocarbon constituents. An intermediate fraction boiling over a relatively narrow boiling range is removed as a side stream by means of line 6.

The relatively low boiling fraction and the relatively high boiling fraction removed by means of lines 4 and 5 respectively may be handled or further refined in any manner desirable. The intermediate boiling side stream is cooled in cooling zone 7 and mixed with an aqueous picric acid solution which is withdrawn from picric acid solution storage 8 and added by means of line 9. The mixture passes through orifice mixer or equivalent means 10 and is introduced into filtering zone 11 by means of line 12. The filtrate is withdrawn from filtering zone 11 by means of line 13, passed to a separator 18 from which unreacted picric acid is returned by means of line 19 to picric acid solution storage 8 and oil by means of line 40 to further handling in any manner desired. The styrene picrate is withdrawn from filtering zone 11 by means of line 14 as a filter cake, is introduced into crushes 15 and then introduced into an agitation zone 16 in which the crushed styrene picrate is washed, preferably with hot water which is introduced by means of line 17. A slurry of styrene picrate is withdrawn from agitation zone 16 by means of line 18 and introduced into distillation zone 19 in which the styrene is removed overhead by means of line 20. Complete removal of the styrene from the slurry of styrene picrate in dilute picric acid solution is secured by means of open steam, which is introduced by means of line 21. The dilute picric acid solution is withdrawn by means of line 22 heated by means of heating zone 23 and introduced into a vacuum evaporator 24. Water is removed overhead from zone 24 by means of line 25 while concentrated picric acid solution is removed by means of line 26 and recycled to aqueous picric acid solution storage 8. The styrene removed overhead by means of line 20 is cooled in cooling zone 27, passed to a separating zone 28 in which the condensed water is removed by means of line 29. The hydrocarbon fraction comprising styrene is removed by means of line 30 and passed into fractionating zone 31. Temperature and pressure conditions are adjusted to remove substantially completely pure styrene as a side stream by means of line 32, to remove overhead by means of line 33 relatively low boiling impurities, and to remove by means of line 34 relatively high boiling impurities. Under certain conditions, it may be desirable to employ solid picric acid rather than a solution of the same for the recovery of styrene. If this operation be utilized, the feed fraction may be passed alternatively through contacting units 35 and

35—a by means of line 36, and the solid styrene picrate removed from the respective units by means of line 37 and handled as described above.

The process of the present invention may be widely varied. Although the operation has been described with respect to stocks derived in the cracking of petroleum oils, it is to be understood that styrene may be recovered from feed streams derived from any source. For example, the operation is particularly applicable in the recovery of styrene from the light oil which is recovered as a by-product in the manufacture of gas. It is also to be understood that the present process may be adapted for the recovery of styrene which is produced from a petroleum oil source by the reaction of ethylene with benzene to form ethyl benzene, which reaction product is subsequently dehydrogenated by a catalytic dehydrogenation operation to produce styrene.

Although solid picric acid may be employed, it is preferred that 1% to 5% solution, preferably aqueous, be utilized. It is also desirable that the solution contact a relatively narrow boiling fraction, as for example, a fraction boiling in the general range from about 280° F. to 310° F., preferably a fraction which boils in the range from about 290° F. to 300° F. When treating a fraction boiling in this range, particularly desirable results are secured providing a 2% aqueous solution of picric acid is employed.

Although the temperatures and pressures may be widely varied depending upon the character of the feed mixtures, the particular picric acid solution, and the like, employed, it has been found that preferred operating temperatures are in the range from about 20° F. to 40° F. Especially desirable temperatures for contacting the picric acid and the styrene containing feed stream are in the range from about 25° F. to about 35° F. In certain operations it may be desirable to employ anti-freezing substances.

When employing a solid picric acid, it is to be understood that any particular size may be employed. The operation may be readily adapted to the use of crystalline picric acid. Such crystals should contain added water to avoid hazards in handling.

Under certain conditions, when treating a feed stream containing styrene and naphthalene, it may not be desirable to segregate the styrene and naphthalene prior to contacting the same with picric acid. Under these conditions, a mixture of styrene picrate and naphthalene picrate is secured. When employing this operation, the styrene picrate is preferably segregated by heating the mixture of picrate crystals in an aqueous picric acid solution under vacuum. The styrene picrate decomposes, while the naphthalene picrate does not. Upon cooling, the naphthalene picrate recrystallizes and may be removed by filtering.

A mixture of styrene picrate and naphthalene picrate, likewise, may be segregated by dissolving the mixture in benzene with the addition of a small quantity of water, and reacting the same with sodium hydroxide solution to free the styrene and naphthalene to the benzene. The styrene there may be reacted with bromine dissolved in carbon tetrachloride to effect the desired separation.

In order to illustrate the invention further, the following example is given which should not be construed as limiting the same in any manner whatsoever.

Example

A petroleum feed oil boiling in the range from about 100° F. to 400° F. was distilled and a fraction boiling in the range from about 290° F. to 300° F. segregated. This fraction was contacted with a 2% picric acid solution at 35° F. to form styrene picrate. The styrene picrate was separated by filtration and washed into a still with hot water at a temperature of 175° F. Care was exercised to maintain the temperature below the melting point of the styrene picrate. This slurry of styrene picrate in dilute picric acid solution in the still was steam distilled; substantially 100% pure styrene was then segregated by condensing oil was recovered by this operation.

What we claim as new and wish to protect by Letters Patent is:

- 25 1. Process for the segregation of styrene from petroleum oils containing the same, which comprises contacting said petroleum oils with aqueous picric acid, segregating styrene picrate and recovering the styrene therefrom.
- 30 2. Process for the recovery of styrene from petroleum oil feed gases containing the same, which comprises contacting the same with an aqueous solution of picric acid, segregating the styrene picrate and recovering the styrene therefrom.
- 35 3. Process for the recovery of styrene from petroleum boiling in the range from about 100° F. to about 400° F., which comprises segregating a fraction boiling in the range from about 280° F. to about 310° F., contacting the same with aqueous picric acid, separating the styrene picrate, and recovering the styrene by distilling the styrene picrate in the presence of steam.
- 40 4. Process for the recovery of styrene, which comprises passing impure styrene into contact with an aqueous solution of picric acid, segregating styrene picrate formed thereby, forming a slurry of styrene picrate, subjecting the slurry to distillation to liberate styrene from its combination with picric acid, separating styrene from the distillation product, and returning picric acid to the contact stage.
- 45 5. Process for the segregation of styrene from a petroleum oil containing the same, which comprises distilling said oil to produce a fraction containing a substantial proportion of styrene, contacting said fraction with an aqueous solution of picric acid, segregating in solid form styrene picrate formed thereby, crushing the styrene picrate, agitating the crushed styrene picrate in the presence of water, distilling the resulting product in the presence of steam, fractionating the styrene-containing distillate obtained thereby to segregate styrene in substantially pure form, concentrating the dilute picric acid solution remaining from the steam distillation, and returning picric acid to the contacting stage.
